UNITED STATES PATENT OFFICE.

JOHN C. ZIEGLER, OF WICHITA FALLS, TEXAS.

STOVE.

1,110,854.

Specification of Letters Patent. Patented Sept. 15, 1914.

Application filed March 30, 1914. Serial No. 828,248.

To all whom it may concern:

Be it known that I, JOHN C. ZIEGLER, a citizen of the United States, and a resident of Wichita Falls, in the county of Wichita 5 and State of Texas, have invented an Improvement in Stoves, of which the following is a specification.

This invention relates to stoves, and more particularly to an improvement in gas heating stoves.

One of the principal objects of the invention is to provide a heating stove adapted to utilize artificial or natural gas to equal advantage, the construction and arrangement of parts being such that a thorough combustion of the gas is assured and maximum utility of the heat units is attained.

Another object of the invention is to provide a stove having means for sufficiently 20 retarding the passage of heat through the stove to utilize the heat both for purposes of radiation and for heating the air used in combustion of the gaseous fuel, previously to the contact of the air with the burner.

25 A further object of the invention is to provide an improved stove of the class described, which will be simple, durable, efficient in operation and inexpensive to manufacture.

30 With these and other objects in view which will become apparent as the description proceeds, the invention resides in the construction, combination and arrangement of parts hereinafter more fully described 35 and claimed, and illustrated in the accompanying drawing in which like characters of reference indicate like parts throughout the several figures, of which—

Figure 1 represents a vertical sectional view taken centrally through the stove, Fig. 40 2 represents a horizontal sectional view on the plane indicated by the line 2—2 of Fig. 1, Fig. 3 represents a similar view taken on the plane indicated by the line 3—3 of Fig. 45 1, and Fig. 4 represents a vertical sectional view taken through the burner on the line 4—4 of Fig. 2.

Referring more particularly to the drawing, the stove comprises a cylindrical body 50 5 supported by a base 6, which is in turn supported by legs 7, said base having an annular portion 8 forming the bottom of the stove; and an inner casing or air tube 9 disposed within the body 5 and spaced on 55 all sides equally from the walls thereof and disposed at its lower end within a circular

opening cut centrally of the base 6. Said base is provided with a pair of concentric upstanding flanges 10 and 11 respectively, the lower end of the body 5 embracing the former on its outer edge and being secured thereto in any desirable manner, the latter flange encircling the lower portion of air tube 9 and being secured to said tube.

A removable cover 12 is positioned upon the upper end of body 5, said cover being provided with an encircling flange 13 disposed above the lower edge 14 of the cover, between which flange and edge the upper end of the body is disposed whereby the cover is kept in position on the body. Surrounding air tube 9, and secured thereto in spaced relation from the bottom 8, is an annular ring or disk 15, which forms a partition dividing the stove into an upper and lower chamber, 70 A and B respectively.

The tube 9 extends nearly to the top of the body portion of the stove, and upon the upper end of the tube rests an annular burner 16 connected by a plurality of hollow 80 arms 17 with a feed pipe 18 which is disposed centrally within tube 9 and at its lower end connects, by means of an elbow 19, with a second pipe 20 projecting at one end through an opening in the base 6 of the 85 stove, and adapted to receive at its outer end 21 any suitable form of mixer, not shown. The burner is of a diameter greater than the diameter of tube 9 and somewhat less than the diameter of the body portion 90 5, and substantially overhangs said tube on all sides, and the burner is formed in cross-section as shown in Fig. 4, having upper walls 22 and 23 disposed substantially at right angles to each other, the wall 22 being 95 somewhat less in width than the wall 23, and forming the outer wall of the burner, and said walls are connected by a substantially U-shaped bottom 24, openings 25 being provided in the walls through which the gas 100 may pass to be burned.

A draft pipe or flue 26 is secured at its lower end to the body of the stove and communicates with the lower chamber B through an opening 27 cut therein, and communicates 105 with the upper chamber A at a point level with the burner 16, through a sleeve 28 having a damper 30 positioned therein. The body 5 opposite sleeve 28 is provided with an opening 31 adapted to be normally 110 closed by a door 32.

The operation of my stove may be briefly

described as follows: The gas having been turned on from the reservoir, may be ignited at the burner 16 through the door opening 31, and the damper 30 turned so as to lie parallel with the axis of sleeve 28, thus creating a draft of air upwardly through the tube 9, through the openings 33 which occur between the several arms 17 of the burner, directly across said burner, through the sleeve 28, and up the pipe 26. The damper will be left open until the pipe has been sufficiently heated to expel the cold air therein, whereupon the damper will be turned crosswise of its sleeve, by which action the current of air coming up through the air tube will be drawn across the burner 16 and downwardly through the chamber A, and will strike the partition 15, and pass through a number of openings 34 cut thereon in the opposite side of the stove from pipe 26, into the lower chamber B, and will be drawn off through the pipe 26.

The heat created within the stove, will raise the air pipe 9 to a high temperature, thus heating the air as it passes upwardly therethrough, and in turn heating the feed pipe 18 to a high temperature, so that the air and gas contained within the feed pipe when reaching the burner will be in the most favorable condition to support combustion. It is a well known fact that in order to attain perfect combustion, there must be one part, by weight, of carbon, and two parts of oxygen, which mixture is carbonic acid. If then an insufficient quantity of air is introduced, the combustion will not be complete and the resultant gas is carbonic oxid, composed of one part carbon and one part oxygen.

The gas passing through the mixing tube to the burner does not mix with a sufficient amount of air contained in the tube to produce complete combustion; however, since the contents of the tube are so thoroughly heated they become as completely mixed as possible, and in this state the mixture is delivered at the burner under the most favorable condition for complete combustion. The gas, however, is not completely consumed, and if no further mixture of oxygen were possible, it would pass off unconsumed, but at this point additional air, heated to a very high temperature within the air tube 9, is introduced to the combustion chamber around the burner and mingling with the unconsumed carbon produces secondary combustion. In other words, the carbonic oxid, by the introduction of additional heated air or oxygen, is transformed into carbonic acid, resulting in complete combustion.

One of the advantages accruing to my stove, worthy of special notice, is that after the burner has been heated, no cold air whatever can be introduced within the com-

bustion chamber, which would tend to reduce the temperature within the stove, and thus effectually defeat the very end sought to be attained by this invention, but the only air admitted is heated to a high temperature before gaining entrance.

The current of heat after leaving the burner will be retarded by reason of the flue opening being at the bottom of the stove, and also by reason of the partition 15, to such an extent, as to allow a great amount of the heat being absorbed by the body of the stove and radiated into the room, the course of the heat being downward around the tube on all sides, until it strikes the partition 15 where it will circulate until it may pass through openings 33 where it will strike against the bottom 8 of the stove, and also against the lower portion of tube 9, before being carried off at the draft pipe 26. The openings 33 have been placed on the opposite side of the stove from the draft pipe, but if so desired they may be placed at any point around the partition 15, or all around the same.

Although I have described the preferred embodiment of my invention, I may desire to make such changes in the construction, combination and arrangement of parts as do not depart from the spirit of the invention and the scope of the appended claims.

I claim:

1. A stove having a hollow cylindrical body, an air tube disposed concentrically with the body and spaced equally on all sides therethrough, a base having an annular flat portion forming the bottom of the stove, upstanding flanges provided on said base, the lower end of said body portion and tube being secured to said flanges, said tube extending through an opening in said base, a burner disposed upon the upper end of said tube, said burner overhanging the tube on all sides, a feed pipe disposed axially within said tube, a plurality of hollow arms connecting said feed pipe to said burner, a cover on said body portion, said body portion having an opening therein in alinement with said burner, a door for normally closing said opening, an annular ring secured within said body portion at the lower end thereof and in spaced relation to the body, said ring disposed between the body portion and air tube, and forming a partition to divide the stove into upper and lower compartments, said ring having a series of openings in one side thereof, a draft pipe connected to said body and opening into the lower chamber below the partition and on the opposite side of the stove from the openings in said ring, a hollow sleeve connecting the upper portion of the body with the draft pipe in alinement with said burner, and a damper positioned in the sleeve.

2. A stove comprising a hollow cylindri-

cal body, an air tube disposed axially within said body and spaced equally therefrom, on all sides, a leg supported base, said base having an annular flat portion to which said body and tube are secured for forming the bottom of the stove, said tube extending through said base and opening into the outside atmosphere, a burner disposed upon said tube and overhanging the same on all sides within the body, a feed pipe connecting said burner with a source of supply, hollow arms connecting said burner with said feed pipe, a top on said body, a partition disposed within the body and forming the same into an upper and lower chamber, said partition having a series of openings therein in one side of the tube, a draft pipe connected to said stove and opening into the lower chamber, means for allowing a draft between the upper chamber and the draft pipe, and means for regulating said draft.

3. A stove comprising a base having an annular flat portion, a hollow cylindrical body disposed on said flat portion, an air tube disposed within said body and extending through said flat portion and secured thereto, a burner disposed on said air tube within the body, a feed pipe connected with said burner and disposed within said tube, a draft pipe connected to said body portion at the lower end thereof and adapted to create a downward draft around the tube, means disposed within the body portion for retarding said downward draft, and means for creating a direct draft between the body and the draft pipe and means for regulating said last draft.

4. A stove providing a combustion chamber, a stove body surrounding the combustion chamber, an air tube disposed concentrically with the body and forming the inner wall of the combustion chamber, a burner disposed on the air tube within the

chamber, a feed pipe disposed within the air tube and connected at one end to said burner and at the opposite end to the fuel supply, a leg supported base having a central opening, means for securing the air tube to the base at the central opening and for securing the body to the base near the periphery of the latter, said base forming a closure for the lower end of the combustion chamber, a top disposed on the stove body and forming a closure for the upper end of said chamber, said body, base, top and air tube adapted in combination to prevent ingress of air into the combustion chamber at any point except through the central opening and air tube, a draft pipe communicating with the lower end of the combustion chamber adapted to create a down draft therethrough, means for establishing a direct draft between the upper end of said chamber and the draft pipe, means for regulating last said draft, a ring disposed within the chamber between said body and air tube and above the connecting point of the draft pipe and lower end of the chamber and forming a partition dividing the chamber into two compartments, said ring having openings therein on the opposite side of the stove from the draft pipe, said ring adapted to retard the down draft and direct the same to said opposite side of the stove and through the openings against the stove bottom, means for preheating all the air used to support combustion before admission to the combustion chamber, and means for preventing the introduction of cold air at any point subsequently to the ignition of the burner.
